UNITED STATES PATENT OFFICE.

OLIVER LAND FRANCIS HAGGARD AND THOMAS OLIN RUSH, OF GADSDEN, ALABAMA.

TRAY.

Application filed March 25, 1922. Serial No. 546,611.

To all whom it may concern:

Be it known that we, OLIVER L. F. HAGGARD and THOMAS O. RUSH, citizens of the United States, residing at Gadsden, in the county of Etowah, State of Alabama, have invented a new and useful Tray, of which the following is a specification.

The device forming the subject matter of this application is a dental impression tray, and the invention aims to provide novel means whereby the impression material may be compressed in the mouth of the patient, to insure a perfect and clear impression.

It is within the province of the disclosure to improve generally and to enhance the utility of devices of that type to which the invention appertains.

In the accompanying drawings:—

Figure 1 shows in top plan, a tray used in the formation of a lower set; Figure 2 is a section on the line 2—2 of Figure 1; Figure 3 is a transverse section showing the mounting of the wings; Figure 4 is a top plan of a tray used in the formation of an upper set; Figure 5 is a section on the line 5—5 of Figure 4; Figure 6 is a rear end elevation of the tray depicted in Figures 4 and 5.

Referring to Figures 1, 2 and 3, the tray comprises a U-shaped body 1 which is trough-shaped in cross section, a projecting handle 2 being secured to the body 1 of the tray as shown at 3, the handle having an opening 4 whereby the tray may be conveniently suspended when not in use. Wings 5 are hinged at 10 to the inner edges of the body 1 and the rear end thereof. Any suitable means may be provided for swinging the wings 5 to secure a compression of the impression material. If desired, the wings 5 may be supplied with eyes 6 wherein the reduced ends 7 of crossed levers 8 are loosely and pivotally received, the levers 8 being fulcrumed at 9 at their point of crossing, on the handle 2.

It is obvious that when the device is placed in the mouth of the patient, the outer ends of the levers 8 may be swung toward each other, thereby moving the rear ends 7 of the levers in an outward direction, the wings 5 swinging laterally and effecting a compression of the material.

In Figures 4, 5 and 6, the tray comprises a body 11 of the usual form employed when

it is desired to make an upper set. Wings 12 are pivoted or hinged at 14 to the outer edge of the body 11 and extend around to the front of the body. A handle 15 is secured at 16 to the body and has a suspension opening 17.

Any suitable means may be employed for swinging the wings 12 inwardly and outwardly. Thus, if desired, the forward ends of the wings 12 may be supplied with eyes 18 wherein the rear ends of operating rods 19 are pivoted, as at 20, the rods 19 being loosely mounted for longitudinal and lateral swinging movement in a guide 21 on the handle 15, the rods terminating at their forward ends in fingers 22 projecting away from the handle 15. When the rods 22 are thrust in the direction of the arrow A in Figure 5, the wings 12 will swing outwardly in the direction of the arrow B in Figure 4, and when the rods 19 are moved in a direction opposite to that indicated by the arrow A in Figure 5, the wings 12 will swing inwardly, in a direction opposite to that indicated by the arrow B in Figure 4, and effect a compression of the impression material.

What is claimed is:—

1. A dental impression tray comprising a handle, a body secured to the handle, wings hinged to the edges of the body for swinging movement toward and away from the prolonged axis of the handle, and means assembled with the handle and with the wings to cause the wings to swing toward and away from the prolonged axis of the handle.

2. A dental impression tray comprising a handle, a body carried by the handle, wings hinged to the edges of the body for swinging movement toward and away from the prolonged axis of the body, a guide on the handle, and operating members mounted in the guide for longitudinal movement and for lateral-swinging movement, the operating members being pivoted to the wings.

In testimony that we claim the foregoing as our own, we have hereto affixed our signatures in the presence of two witnesses.

OLIVER LAND FRANCIS HAGGARD.
THOMAS OLIN RUSH.
